[57] CLAIM

The ornamental design for a corner junction element, substantially as shown and described.

DESCRIPTION

FIG. 1 is a side, perspective view of a corner junction element with removable ear showing my design;

FIG. 2 is a side, perspective view of the corner junction element according to FIG. 1 shown from the opposite side;

FIG. 3 is a side, perspective view of the corner junction element according to FIG. 1 with removed ear;

FIG. 4 is a side, perspective view of the corner junction element according to FIG. 3 shown from the opposite side;

FIG. 5 is a side, perspective view of a corner junction element according to a modified embodiment of my design; and

FIG. 6 is a side, perspective view of the corner junction element according to FIG. 5 shown from the opposite side.

FIG. 1

FIG. 2

FIG. 3

FIG. 4

FIG. 5

FIG. 6
